(57) CLAIM

The ornamental design for a bagger, as shown and described.

DESCRIPTION

FIG. 1 is a front perspective view of a bagger showing our new design;

FIG. 2 is a side perspective view thereof;

FIG. 3 is a right side view thereof;

FIG. 4 is an end view thereof;

FIG. 5 is a top perspective view with the sides extended out thereof; and,

FIG. 6 is a top side view thereof.

The broken lines in the Figures are for illustrative purposes only and form no part of the claimed design.
